LOCOMOTIVE TENDER

Howard P. Anderson, Erie, Pa., and Charles J. Surdykowski, Tuckahoe, N. Y.; said Surdykowski now by judicial change of name Charles J. Surdy, assignors to Standard Stoker Company, Incorporated, a corporation of Delaware

Application November 12, 1930, Serial No. 495,142
Renewed March 16, 1932

34 Claims. (Cl. 105—234)

Our invention relates to locomotive tenders in which stoker mechanism is used and has for one of its main objects the provision of a tender constructed to permit mounting the stoker drive mechanism comprising either gearing, the stoker engine, or both in a compartment adjacent or back of the rearward end of the stoker fuel trough. The invention further contemplates forming a tender and its stoking mechanism so that the conveyor screw may be withdrawn and replaced from the rearward end of the tender without the necessity, as exists in present practice, of uncoupling the locomotive and tender.

10 Other objects such as providing a stoker gear casing removably mounted in a water tight compartment at the rear of the stoker trough to form a closure between the open rearward end of the trough or the fuel bin and the aforesaid compartment will presently appear from the drawings and following description which describes in a specific manner a preferred and a modified form of this invention. Our invention in the forms shown and in other modifications within its scope is applicable to all known types of locomotive tenders suitable for stoking mechanism.

On the drawings

Fig. 1 is a central vertical longitudinal section of a locomotive tender and a portion of the stoking mechanism;

30 Fig. 1a is a fragmentary transverse section on the line 1a—1a of Fig. 1;

Fig. 2 is a plan section on the line 2—2 of Fig. 1;

35 Fig. 3 is a section on the line 3—3 of Fig. 1;

Fig. 4 is a central vertical longitudinal section of a modified form of the tender and stoker mechanism of Fig. 1; and

Fig. 5 is a plan section on the line 5—5 of Fig.

40 4. The locomotive tender is indicated generally at 10 and a portion of the locomotive at 11. The tender body portion is formed with the fuel compartment 12 and the water compartment 13 separated from each other by the rear slope sheet 14, the side slope sheets 14a, fastened at their lower marginal portions, as best shown in Figs. 1, and 1a, to a trough member 15 to form a water tight partition wall. The trough 15 at its forward end is joined to suitable plates to form a forward closure for the water section.

50 The tender base or frame is shown at 16 and comprises the side sills 16a, the center sills 16b, the bottom web or base plate 17 and a top web or upper plate 18 connected by the transverse

transoms or ribs 19, and extends from one end of the tender to the other. The base plate 17 is solid, but the upper plate 18 has a series of perforations 20, and the ribs are apertured at 21, so that water from the water compartment can circulate freely in the space between the two plates 17 and 18. The trough member 15 is shown in the drawings as an integral part of the frame 16 disposed within the water section, but it will be obvious that it may be formed as a separate 10 member supported from the frame by suitable foot members.

5 The floor 22 of the fuel compartment 12 is provided with a central longitudinal opening 23 communicating with the trough 15 and through 15 which fuel is supplied to the trough by gravity. Plates 25 are slidably mounted in the opening 23, and may be moved from covering position to permit entry of the fuel into the trough as the supply becomes depleted.

20 The trough 15 communicates with a bowl 26 through an opening 27 in its forward end. The bowl 26 is received in a spherical portion of the vertically split coupling member 28 carried by the tubular section 29 which leads forwardly to 25 deliver fuel to the locomotive firebox in any suitable manner.

25 Suitable mechanism is employed for crushing and for conveying fuel, including a screw 30 mounted in the trough 15 and extending longitudinally forward into the bowl 26 and a crushing abutment 31 at the forward end of the trough and arched over the screw 30 for engaging the fuel to crush it to a proper size for firing.

30 Referring now more particularly to Figures 1, 2 and 3, the trough 15 opens rearwardly into a water-tight compartment 32 which extends transversely of the tender and opens through the upright exterior side wall 33 thereof. The compartment 32 comprises the front wall 34, the rear wall 35, the top wall 36 and the side wall 37. The upper plate 18 of the tender frame 16 forms the bottom wall of the compartment 32 and the removable cover 38 in the tender sidewall 33 forms the other sidewall thereof. The rear wall 35 of the compartment 32 is provided with an opening 39 communicating with a sleeve 40 which extends longitudinally of the tender along the extended axis of the screw 30 opening rearwardly in 50 the upright rear wall 41 of the tender. A detachable cover 42 forms a closure for the rearward opening of the sleeve 40. The plates constituting the walls forming the compartment 32 may be secured in any suitable manner to a framework

consisting of the upright angle bars 32a and the horizontal angle bars 32b.

The compartment 32 houses the stoker driving mechanism making it easily and conveniently accessible for purposes of inspection, repair and replacement through the opening in the side of the tender by removing the cover 38. The driving mechanism comprises a motor 43 mounted in the compartment 32 at one side of the openings to the trough 15 and the sleeve 40 and a gear casing 44 removably mounted in the compartment 32 normally forming a closure for the opening to the trough 15. The motor 43 operates the drive shaft 45 which transmits motion to the shaft 46 coupled to the drive shaft 45 by the coupling member 47. The gear 48 carried by the shaft 46 engages the gear 49 mounted on the shaft 50 transmitting motion thereto, which in turn operates the screw 30. This arrangement permits withdrawal of the screw 30 through the compartment 32 and the sleeve 40 without necessitating uncoupling of the locomotive and tender. It may be done conveniently by removing the bolts 51, removing the coupling 47, drawing the shaft 45 apart from the shaft 46 permitting sufficient clearance for withdrawing the gear casing 44.

Figures 4 and 5 illustrate a modified arrangement in which a motor and gear housing compartment 52 extending transversely of the tender is located at the rear thereof. This compartment 52 forms a recess in the water compartment at one of the rear corners, enabling the drive mechanism to be mounted outside or exteriorly of the water compartment and shielding the drive mechanism from the water therein. The opening through which access to the interior of the compartment 52 is gained is in the rear upright wall of the tender and is closed by the removable cover 53. A longitudinally extending sleeve 54 communicates at its forward end with an opening in the rearward end of the trough 15 and at its rearward end with an opening in the front wall of the compartment 52. A screw conveyor 55 is mounted in the trough 15 and extends rearwardly into the sleeve 54 for a few turns. The flights of the screw 55 in the sleeve 54 have a larger diameter than the remaining flights and slightly less than the diameter of the sleeve to fit snugly therein. When clogging or jamming occurs it is usual to reverse the screw 55 for about a half a turn to relieve it, and some fuel will be carried into the sleeve 54. This fuel will be swept back into the trough by the enlarged flights in the sleeve when the screw is again rotated to advance fuel. The shaft 56 of the screw conveyor 55 extends rearwardly into the compartment 52 and is supported by the bearing 57 which forms a closure for the opening between the sleeve 54 and the compartment 52.

The screw conveyor 55 is operated by a motor 58 through gearing 59, in the same manner in which the screw 30 in the preferred form is driven. The screw 55 may readily and conveniently be withdrawn through the rear of the tender by removing the cover 53, removing the coupling member 60, detaching the gear housing from the floor of the compartment 52 and withdrawing the screw 55 rearwardly through the sleeve 54 and the compartment 52.

We claim:

1. In combination in a locomotive tender having a base, a body portion with partition walls separating the fuel section from the water section thereof, said sections arranged to receive a stoker

trough having a conveyor therein, and a water tight compartment formed in said water section immediately rearward of said trough extending transversely thereof intermediate the ends of the tender and opening through an upright sidewall of the tender, said compartment housing drive mechanism for said trough conveyor.

2. In combination in a locomotive tender having a base, a body portion with partition walls separating the fuel section from the water section thereof, said sections arranged to receive a stoker trough having a conveyor screw therein, a water tight compartment formed in said water section rearward of said trough extending transversely thereof and opening through a wall of the tender, said compartment housing drive mechanism for said trough conveyor screw, and a sleeve extending longitudinally of the tender on the extended axis of said screw and at one end opening into said compartment, through which compartment and sleeve the screw may be removed from the rearward end of the tender.

3. In combination in a locomotive tender having a base, a body portion with partition walls separating the fuel section from the water section thereof, said sections arranged to receive a stoker conveyor, and a water tight compartment immediately rearward of said conveyor extending transversely of said tender and being intermediate the ends thereof for housing the stoker conveyor drive mechanism, said compartment at one side opening through an upright sidewall of the tender.

4. In combination with a locomotive tender having a base, a body portion with partition walls separating the fuel section from the water section thereof, said sections arranged to receive a stoker conveyor, and a water tight compartment for housing stoker drive mechanism formed in said body portion adjacent, and providing access to, the rearward end of said stoker conveyor, said compartment extending transversely of one side of said tender and opening through an upright sidewall thereof.

5. In combination with a locomotive tender having a base, a body portion with partition walls separating the fuel section from the water section thereof, said sections arranged to receive a stoker conveyor, a water tight compartment for housing stoker drive mechanism formed in said body portion adjacent, and providing access to, the rearward end of said conveyor, and a sleeve extending longitudinally of the tender on the extended axis of said conveyor and at one end opening into said compartment and at the other opening through the rear wall of the tender.

6. In combination with a locomotive tender having a base, a body portion with partition walls separating the fuel section from the water section thereof, said sections arranged to receive a stoker trough having a screw conveyor therein, a water tight compartment formed in said water section at the rearward end of said trough, said trough at its rearward end opening into said compartment, a gear casing detachably mounted in said compartment to form a closure between the rear end of said trough and said compartment, gearing in said casing associated with said screw, a stoker engine removably mounted in said compartment and having a driving connection with said gearing and said compartment opening through an upright sidewall of the tender to provide access to and permit removal of said casing, gearing and engine.

7. In combination with a locomotive tender

having a base, a body portion with partition walls separating the fuel section from the water section thereof, said sections arranged to receive a stoker trough having a screw conveyor therein, 5 a water tight compartment formed in said water section at the rearward end of said trough, said trough at its rearward end opening into said compartment, a gear casing detachably mounted to form a closure between the rear end 10 of said trough and said compartment, gearing in said casing associated with said screw, a stoker engine removably mounted in said compartment and having a driving connection with said gearing, said compartment opening through an exterior wall of the tender to provide access to and 15 permit removal of said casing, gearing and engine, and a sleeve extending longitudinally of the tender on the extended axis of said screw and at one end opening into said compartment 20 and at the other opening through the rear wall of the tender whereby upon removing the gear casing said screw may be removed from the rearward end of said tender through said sleeve.

8. In combination with a locomotive tender 25 having a base, a body portion with partition plates separating the fuel section from the water section thereof, a stoker trough formed in said sections and arranged to form the bottom portion of said fuel section, a water tight compartment at the rear of said trough and having an opening through an upright sidewall of 30 said tender, said trough at its rearward end opening into said compartment, and a detachable gear casing normally forming a closure for the opening between the trough and said compartment.

9. In combination with a locomotive tender having a base, a body portion with partition plates separating the fuel section from the water section thereof, a stoker trough formed in said sections and arranged to form the bottom portion of said fuel section and being spaced above said base and arranged therewith to provide communicating water space underneath said plates 45 and beneath said trough, a water tight compartment for housing stoker drive mechanism formed in said water section at the rear of said fuel trough, said compartment opening through an upright sidewall of the tender and said trough 50 at its rearward end opening into said compartment, and a gear casing removably mounted in said compartment normally forming a closure between said compartment and said trough.

10. In combination with a locomotive tender 55 having a base, a body portion with partition walls separating the fuel section from the water section thereof, a stoker trough formed in said sections and arranged to form the bottom portion of said fuel section, a conveyor screw in said trough, a water tight compartment for housing stoker drive mechanism formed at the rearward end of the tender and having an opening through a sidewall thereof, and a sleeve extending between the rearward end of said trough and said compartment, said sleeve being disposed longitudinally of the tender on the extended axis of 60 said screw and at one end opening into said trough and at the other opening into said compartment whereby said screw may be removed from the rearward end of the tender.

11. In combination with a locomotive tender having a base, a body portion with partition walls separating the fuel section from the water section thereof, a stoker trough formed in said sections and arranged to form the bottom portion of

said fuel section, a conveyor screw in said trough, a water tight compartment for housing stoker drive mechanism formed at the rearward end of the tender and having an opening through a sidewall thereof, a sleeve extending between the rearward end of said trough and said compartment, said sleeve being disposed longitudinally of the tender on the extended axis of said screw and at one end opening into said trough and at the other opening into said compartment, said screw extending rearwardly into said sleeve and that portion of its vanes within said sleeve having a diameter substantially the same as the internal diameter of the sleeve, a gear casing inclosing 10 gearing mounted in said compartment, a stoker 15 engine in said compartment having a driving connection with said gearing, and a shaft extending into said sleeve connecting said screw with said gearing.

12. In combination with a locomotive tender 20 having a base, a body portion with partition walls separating the fuel section from the water section thereof, a stoker trough formed in said sections arranged to form the bottom portion of said fuel section, a conveyor screw in said trough, a compartment separated from the water section formed at the rear end of the tender, stoker drive mechanism within said compartment, a sleeve extending between said compartment and the rearward end of said trough, said sleeve being disposed 25 longitudinally of the tender on the extended axis of said screw and at one end opening into said trough and at the other opening into said compartment, and a drive connection extending within said sleeve connecting said screw with said drive mechanism.

13. In combination with a locomotive tender having a base, a body portion with partition walls separating the fuel section from the water section thereof, a stoker trough formed in said sections arranged to form the bottom portion of said fuel section, a conveyor screw in said trough, a compartment separated from the water section formed at the rear end of the tender, stoker drive mechanism within said compartment, a sleeve 40 extending between said compartment and the rearward end of said trough, said sleeve being disposed longitudinally of the tender on the extended axis of said screw and at one end opening into said trough and at the other opening into 45 said compartment, a drive connection extending within said sleeve connecting said screw with said drive mechanism, said screw extending rearwardly into said sleeve and the screw vanes within the sleeve being of larger diameter than the 50 screw vanes within said trough.

14. In combination with a locomotive tender having a base, a body portion with partition walls separating the fuel section from the water section thereof, a stoker trough formed in said sections arranged to form the bottom portion of said fuel section, a conveyor screw in said trough, a compartment separated from said water section formed at the rear end of the tender, stoker drive mechanism within said compartment, a sleeve extending between said compartment and the rearward end of said trough, said sleeve being disposed longitudinally of the tender on the extended axis of said screw and at one end opening into 60 said trough and at the other opening into said compartment, and a drive connection extending within said sleeve connecting said screw with said drive mechanism, said screw extending rearwardly into said sleeve and the screw vanes within the sleeve being of larger diameter than the screw 65

70

75

- vanes within said trough, the diameter of the vanes within the sleeve being slightly less than the internal diameter of the sleeve to form a close fit providing a seal against backward movement of the fuel during its normal forward movement.
15. In combination with a locomotive tender having a base, a body portion with partition walls separating the fuel section from the water section thereof, a stoker trough formed in said sections arranged to form the bottom portion of said fuel section, a conveyor screw in said trough, a compartment separated from the water section formed at the rear end of the tender, stoker drive mechanism within said compartment, a sleeve extending between said compartment and the rearward end of said trough, said sleeve being disposed longitudinally of the tender on the extended axis of said screw and at one end opening into said trough and at the other opening into said compartment, a drive shaft extending within said sleeve connecting said screw with said drive mechanism, and a bearing member for said drive shaft detachably mounted to form a closure for the opening between said sleeve and said compartment.
16. The combination in a locomotive tender having a base frame and fuel and water compartments, of a stoker conveyor mounted in said tender at the front end portion thereof to receive fuel from said fuel compartment, stoker drive mechanism mounted above said frame at the rear of the tender shielded from the water in said water compartment, and a drive shaft operated by said drive mechanism extending through said water compartment, said drive shaft and stoker conveyor having adjacent portions which are operatively connected in end to end relation.
17. The combination in a locomotive tender having a base frame and fuel and water compartments, of a stoker conveyor screw mounted in said tender at the front end portion thereof to receive fuel from said fuel compartment, stoker drive mechanism mounted above said frame at the rear of the tender shielded from the water in said water compartment, a drive shaft operated by said drive mechanism extending through said water compartment, said drive shaft and conveyor screw having adjacent portions which are operatively connected in end to end relation, and a sleeve surrounding that portion of said drive shaft within the water compartment.
18. In combination with a locomotive tender having a base, a body portion with partition plates separating the fuel section from the water section thereof, a stoker trough formed in said sections and arranged to form the bottom of said fuel section and being spaced above said base and arranged therewith to provide communicating water space underneath said plates and beneath said trough, a water tight compartment for housing stoker drive mechanism formed in said water section at the rear of said fuel trough, said compartment opening through a wall of the tender and said trough at its rearward end opening into said compartment, and a gear casing removably mounted in said compartment normally forming a closure between said compartment and said trough.
19. In combination with a locomotive tender having a base, a body portion with partition walls separating the fuel section from the water section thereof, a stoker trough formed in said sections and arranged to form the bottom portion of said fuel section, a conveyor screw in said trough, and a sleeve rearward of said trough disposed longitudinally of the tender on the extended axis of said screw and at one end opening through the rear wall of the tender and at the other being arranged to communicate with the rear end of the trough, whereby said screw may be removed rearwardly of the tender through the sleeve.
20. In combination with a locomotive tender having a base, a body portion with partition walls separating the fuel section from the water section thereof, a stoker trough mounted on the tender to receive fuel from said fuel section, a conveyor screw in said trough, and a water tight sleeve in said water section rearward of said trough disposed longitudinally of the tender on the extended axis of said screw and at one end opening through the rear wall of the tender and at the other being arranged to communicate with the rear end of said trough, whereby said screw may be removed rearwardly of the tender through the sleeve.
21. A locomotive tender comprising a base, a body portion with partition plates forming fuel and water sections, a stoker trough mounted to receive fuel from said fuel section, and a water tight sleeve in said water section rearward of said trough disposed longitudinally of the tender and at one end opening into said trough and at the other through an upright wall at the rear of the tender.
22. A locomotive tender comprising a base, a body portion with partition plates forming fuel and water sections, a stoker trough mounted to receive fuel from said fuel section, a water tight sleeve in said water section rearward of said trough disposed longitudinally of the tender and at one end opening into said trough and at the other through an upright wall at the rear of the tender and a screw conveyor extending within said trough and said sleeve.
23. In a locomotive tender, a base, a body portion above said base with partition walls forming fuel and water sections, a stoker trough mounted to receive fuel from said fuel section, a water tight sleeve in said water section rearward of said trough disposed longitudinally of the tender and at one end opening into said trough and at the other through an upright wall at the rear of the tender, a screw conveyor extending within said trough and said sleeve, and means on the tender for driving said screw.
24. In a locomotive tender, a base, a body portion above said base with partition walls forming fuel and water sections, a stoker trough mounted to receive fuel from said fuel section, a water tight sleeve in said water section rearward of said trough disposed longitudinally of the tender and at one end opening into said trough and at the other through an upright wall at the rear of the tender, a screw conveyor extending within said trough and said sleeve, and means on the tender above said base and rearward of said upright wall for driving said screw.
25. In a locomotive tender having a water-bottom underframe, a stoker trough forming the top wall of a portion of the water chamber, framework for a stoker engine compartment extending laterally from said trough, and elements forming the floor for said compartment and the top wall of a water chamber beneath said compartment.
26. In a locomotive tender, an underframe, a stoker trough located over the central portion

5 of the underframe, and a stoker engine compartment extending from the rear of said trough to the side of the tender, there being an opening in the side of the tender for access through one end of said compartment, and there being tank walls at the opposite end, and at the front, rear, top, and bottom of said compartment.

10 27. In a locomotive tender underframe, a horizontal web forming the bottom of the tank, a center sill, a side sill, transverse transoms extending upwardly from said web, and a horizontal top web between said sills and transoms forming the bottom wall of a stoker engine compartment.

15 28. In a water-bottom underframe for a locomotive tender, center sills, side sills, transverse transoms between said sills, a horizontal web between the lower portions of said sills and transoms, a horizontal top web between the upper portions of said sills and transoms, said parts forming a liquid compartment, and said top web also forming the floor of a stoker engine compartment.

20 29. In a locomotive tender, a water-bottom underframe having center sills, side sills, transverse transoms between said sills, a horizontal web between the lower portions of said sills and transoms, and a horizontal top web between the upper portions of said sills and transoms, said parts forming a liquid compartment, and a stoker engine compartment framework located over said top web.

25 30. In a locomotive tender, a water-bottom underframe including side sills, a stoker trough and stoker engine compartment framework

mounted on said underframe, and superstructure plates secured to said sills, trough and framework whereby a liquid storage chamber is formed in part by the sides of said trough and compartment and extending over and beneath the latter. 5

31. In a locomotive tender, an underframe including a stoker trough and an imperforate bottom web forming the tank bottom, superstructure including a tank and a coal hopper, an open box-like framework extending laterally from the rear end of said trough and having elements for mounting a stoker engine, and plates secured to said framework and forming walls for said tank.

32. In a locomotive tender, an underframe including a stoker trough, and an integral stoker engine mounting structure extending laterally from the rear end thereof, said underframe having upright elements supporting said structure.

33. In a locomotive tender, an underframe including a vertical side sill and a center sill, a conveyor trough, a frame structure extending rearwardly and transversely therefrom and supported on said sills and opening through an upright wall of the tender conveyor driving mechanism mounted in said frame structure, and a liquid storage compartment substantially surrounding said mechanism.

34. In a locomotive tender, an underframe including a stoker trough and an integral stoker engine mounting structure extending laterally from the rear end thereof.

HOWARD P. ANDERSON.
CHARLES J. SURDYKOWSKI.
